UNITED STATES PATENT OFFICE.

GEORGE A. HENDERSON, OF MANSFIELD, TEXAS.

COMBINED EDUCATIONAL CHART, DRAWING-BOARD, AND WRITING-DESK.

1,084,331.

Specification of Letters Patent.

Patented Jan. 13, 1914.

Application filed March 18, 1912. Serial No. 683,573.

To all whom it may concern:

Be it known that I, GEORGE A. HENDERSON, citizen of the United States, residing at Mansfield, in the county of Tarrant and 5 State of Texas, have invented certain new and useful Improvements in Combined Educational Charts, Drawing-Boards, and Writing-Desks, of which the following is a specification.

10 This invention relates to improvements in combined educational charts, drawing boards, and writing desks, and has for one of its objects to improve the construction and increase the efficiency and utility of devices of this character.

15 Another object of the invention is to provide a device of this character wherein provision is made for rigidly supporting the parts when in open position and to enable 20 them to be folded within a small space when not in use.

With these and other objects in view, the 25 invention consists in certain novel features of construction as hereinafter shown and described, and then specifically pointed out in the claim, and in the drawings illustrative of the preferred embodiment of the invention: Figure 1 is a perspective view of the 30 improved device arranged as a writing desk; Fig. 2 is a vertical sectional elevation with the parts arranged as shown in Fig. 1; Fig. 3 is a view similar to Fig. 1 with the parts folded or collapsed; Fig. 4 is an enlarged sectional detail on the line 4—4 of Fig. 3.

35 Corresponding and like parts are referred to in the following description and indicated in all the views of the accompanying drawings by the same reference characters.

The improved device comprises main supporting legs 10—11 spaced apart and provided with a scroll-supporting frame represented as a whole at 12 at the upper part and divided intermediate the ends by a transverse brace member 13, the latter being 45 supported by suitable braces 14.

Pivotedly connected at 15—16, to the main leg members 10—11, just below the frame 12, are the rear supporting braces 17—18. The legs 17—18 when extended 50 rearwardly at their lower ends, support the main legs 10—11 in a rearwardly inclined position, as shown in Figs. 1 and 2.

Extending between the rear legs or braces 17—18 at the upper portion, is a rack device 55 represented as a whole at 19, and divided by partitions 20 into a plurality of pockets or

receptacles for paper, envelopes, cards and the like, the contents of the pockets being retained in position by a plurality of transverse strips or guards 21. At its upper edge 60 the supporting member 19 is provided with a transverse member 22 having a concaved upper face to form a relatively long receptacle for pencils, rulers or the like. The rear legs or braces 17—18 are connected and 65 supported by diagonal braces 23.

Formed in the inner or confronting faces of each of the main leg members 10—11, is a relatively long pocket or recess one of which is shown at 24, and pivoted at 25 in each of 70 the pockets at its lower end is a plate or bar 26 while similar plates or bars 27 are pivoted at 28 to the outer faces of the rear legs or braces 17—18. At their confronting ends the plates 26—27 are pivotally united at 29 75 and overlap for a considerable distance. Each of the plates 26 is provided with an inwardly directed stop lug 30 which bears over the contiguous edge of the other plate 27, and thus serves as a stop to limit the 80 downward movement of the plates beyond a horizontal line as shown in Figs. 1 and 2, while at the same time leaving them free to be folded upwardly into parallel relations as shown in Fig. 3. By this arrangement it 85 will be noted that the plates 26—27 when in extended position, form effectual supports to retain the brace members 17—18 in position rearwardly of the main legs 10—11, and thus support the latter firmly in position, 90 and when the plates are "broken" upwardly they assume a position face to face and substantially in parallel relations and are received into the pockets or recesses 24 and are thus disposed out of sight and out 95 of the way, and enable the legs 17—18 to fold into relatively close relations to the legs 11—12 and to be partly inclosed by the same as shown in Figs. 3 and 4. By this simple means the legs are closely folded 100 when the device is not in use, or when leaning against a wall. The plates 26—27 form effectual braces to prevent the accidental collapse of the device when being moved from place to place while at the same time 105 are readily foldable when not in use.

Extending between the leg members 10—11, is a combined desk and blackboard member formed with an intermediate body portion 31, and enlarged end members 110 32—33. One face of the body 31 will be employed as a desk, and the other face pro-

vided with a blackboard surface. The side members 32-33 are pivotally united at 34-35 to the confronting faces of the leg members 10-11, and the pivots are so located that when the member 31-32-33 is turned into position substantially parallel with the legs 10-11, one edge of the body 31 will be disposed in close proximity to the lower edge of the scroll frame 12, while the opposite edge of the body will be disposed in close relations to the transverse member 13, as shown in Fig. 3. The rear leg members or braces 17-18 are provided with notches 37 to receive the rear or lower terminals of the members 32-33 and thus prevent the combined desk and blackboard member from being moved beyond a horizontal position as shown in Figs. 1 and 2, while at the same time free to be moved in the opposite direction, as will be obvious.

Attached to one of the rear leg members, for instance the leg member 18, is a stop member preferably formed of wire, and represented as a whole at 38, and connected in any suitable manner, as for instance by staples 39 to the member 18, and with a lateral offset 40 at the upper end which projects a sufficient distance to support the member 33 in its horizontal position, while at the same time releasable by compressing the same when the combined desk and blackboard is to be folded. The member 38 being of relatively long inclined shape, will be displaced automatically by the movement of the member 33 when the combined desk and blackboard is adjusted in its horizontal position, but will require to be manually actuated to release the desk and blackboard.

The frame 12 is hollow, and mounted for rotation within the frame are rollers 41-42 spaced apart and adapted to be rotated by handles or knobs 43-44 projecting through the side members 11. The frame 12 is likewise provided with a transverse supporting member 45 whose forward face is in alignment with the forward sides of the rollers. A flexible sheet or web 46 is connected to the rollers and windable from one to the other and designed to contain drawing lessons, penmanship lessons, or other similar matter, and readable through the open front face of the frame. The "scroll" thus con-

structed it will be noted, is in convenient position above the blackboard and desk member so that the figures upon the scroll 55 are in convenient position for observation by the student from either the desk or the blackboard portion of the device.

The improved device is simple in construction, can be inexpensively manufactured of any light material, and will be very useful for children in studying drawing or penmanship, and may likewise be employed for all the purposes for which an ordinary desk is used.

Having thus described the invention, what is claimed as new is:

In a combined desk and blackboard, the combination of an outer frame including a pair of legs, an inner frame including a pair 70 of legs and a receptacle at the upper part of said legs, pivots at the upper ends of the latter legs to pivotally connect the two frames together, the front edges of the legs of the inner frame having V-shaped notches, 75 the upper walls of said notches being horizontal, said horizontal walls being slightly above the plane of the bottom of the receptacle, a board pivoted to the inner sides of the legs of the outer frame and provided at 80 its two opposite sides with members which extend slightly above the surface of the board, the rear ends of the side members being beveled and fitting in the V-shaped notches when the board is tilted to a horizontal position, the rear portion of the upper surface of the board between the members engaging with the bottom of the receptacle when the ends of the side members engage in the notches, fastening devices on 90 the front edge of the legs of the inner frame to engage with the underside of the side members to lock the board in horizontal position, and means between the inner and outer legs to prevent the latter moving in- 95ward or outward when the board is in a horizontal position.

In testimony whereof I affix my signature in presence of two witnesses.

GEORGE A. HENDERSON. [L. S.]
